Primary Examiner—Robin V. Webster*Assistant Examiner*—Karen E Kearney(74) *Attorney, Agent, or Firm*—Gifford, Krass, Sprinkle, Anderson & Citkowski, P.C.(57) **CLAIM**

The ornamental design for a dog bone, as shown and described.

DESCRIPTION

FIG. 1 is a top plan view illustrating a preferred embodiment of the dog bone of the invention;

FIG. 2 is a left side elevation view thereof, which is a mirror image of the right side thereof;

FIG. 3 is a bottom plan view thereof;

FIG. 4 is a front elevation view thereof;

FIG. 5 is a rear elevation view thereof, wherein the dog bone is rotated 180 degrees; and,

FIG. 6 is a sectional view taken along line 6—6 in FIG. 1.
